UNITED STATES PATENT OFFICE.

ISAAC N. PILLSBURY AND NATHANIEL E. WARREN, OF CLEVELAND, OHIO.

IMPROVEMENT IN RAILROAD TURN-OUTS.

Specification forming part of Letters Patent No. 41,018, dated December 22, 1863.

To all whom it may concern:

Be it known that we, ISAAC N. PILLSBURY and NATHANIEL E. WARREN, of Cleveland, in the county of Cuyahoga and State of Ohio, have invented new and useful Improvements in Railroad Turn-Outs; and we do hereby declare that the following is a full and complete description of the construction and operation of the same, reference being had to the accompanying drawings, making part of this specification, in which—

Figure 1 is a plan view showing both ends of the double track, with the intervening track broken out. Fig. 2 shows one end of the turn-out formed with "frogs" or cast-iron turn-out plates, and Fig. 3 shows the principle and form of the turn-out track as put down for use.

The nature of my invention consists in having both ends of the turn-out alike in the center line of the street or main track, and having the rails for a double track so arranged that upon entering the turn-out the rail of the left-hand track may be curved to any desired radius, commencing the curve of the track at the commencement of the turn-out, and the right-hand track being straight and tangent to the commencement of the curves of the left-hand track, and is continued straight any required distance beyond the frog or crossing of the rails of the two tracks, and then curving to the right and left, forming a reversed curve with any required radius, in such a manner that a tangent to the termination of the reverse curve shall be parallel with the main line of the track or center line of the street or main line and distant therefrom equal to the required distance from center to center of the two tracks, and then the curve continued left and right in such a manner as to form a second reverse curve, terminating in a tangent at the opposite end of the turn-out in the center of the street or line of the main track.

Fig. 1 is a plan view representing the track and turn-out, showing the two ends as formed by so curving and cutting the rails that the use of cast-iron turn-out plates and frogs is dispensed with, the middle being broken to show that the ends can be connected in such a manner as to suit any desired length of turn-out. Fig. 2 shows one end of the turn-out as formed

with cast-iron turn-out plates E and F and frog I and guard-rails G and H. Fig. 3 shows the principle and relative proportions of a turn-out track as put down for use, with dotted lines showing the radii of the curves in the direction of their centers.

The turn-out is so constructed that the cars upon entering it at each end will move along the line of the main track and pass by all the points of the double track in a straight line, thereby avoiding the difficulty of turning off from a straight line to that of a curved line and the consequent liability of running off the track—that is, a car entering the turn-out at A, Fig. 3, will move along the track A C B in a straight line to C, and thence along an easy curve to the end of the turn-out at B, while a car entering the turn-out at B will move along the track B D A in a straight line to D, and thence along an easy curve to the end of the turn-out at A.

At each end of the turn-out cast-iron plates E and F, Fig. 2, with suitable chairs attached for connecting the rails thereto, are used to form the commencement of the double track, the inside plate, F, having a guard thereon, and shown at G, which, in connection with the adjoining guard H, forms a guide for the cars while passing off from the curve upon or to the straight line or main track on leaving the turn-out.

At each end of the turn-out, where the rails of the two tracks cross each other, a cast-iron crossing-plate or frog, I, is used, with suitable chairs attached for connecting the rails of the two tracks.

Turn-outs may be constructed without the cast-iron plates, frogs, and guard rails by curving and cutting the rails of the track, as shown in Fig. 1. Every part of the turn-out is a fixture, requiring no movement to switch the cars, and besides they are not liable to get out of order. The curves are easy, so that the cars can pass each other safely without the liability of running off the track in the usual mode of construction.

The turn outs can be made of any desired length or width between the two tracks, and any kind or size of rails may be used in the construction of the turn-out by making the turn-

out plates and frogs to suit the rails, without changing the form or principle of the turn-out.

The chairs for connecting the ends of the rails of the track to the plate and frog can be made to suit any kind or size of rails.

This turn-out can be used where the main line or track is on a curve, as well as though it were on a straight line. The curves of the turn-out can be as easy as desired, so as to be suitable for either street or locomotive railroads.

As both ends of the turn-out are alike, the same set of plates or frogs will answer for either end, avoiding thus the necessity of making two sets of patterns. It will be noted that the guard at H swells out toward the rail, so as to form an easy plane or curve, thereby causing the wheels as they pass off the curve to the straight track to do so without jamming,

jolting, or straining the wheels and axle or the track. By this arranged track the cars in all cases pass off the turn-out from a curve to a straight line without any movable switch.

What we claim as our invention, and desire to secure by Letters Patent, is—

The herein-described mode of adjusting the tracks and turn outs of street and other railroads, so that the cars from either end of the tracks can enter upon the turn-out in straight lines from either end and pass the two points of intersection at either end before making or entering upon the curve, in the manner and form as herein set forth.

I. N. PILLSBURY.
N. E. WARREN.
